LAPEL FASTENER

Max H. Gronauer, Memphis, Tenn.

Application January 23, 1935, Serial No. 3,105

4 Claims. (Cl. 24—81)

This invention relates to new and useful improvements in lapel fasteners.

The primary object of the invention is to provide a device which may be employed by the cleaners' and dyers' trade, tailors, or haberdashers for holding the lapels of coats in their proper positions so that they will not be crumpled, improperly creased, or become out of shape while being handled when on display or during delivery.

10 A further object of the invention is to provide a lapel fastener which is of exceedingly simple construction and which may be easily and quickly applied to the lapels of a coat, or the like.

15 Other objects and advantages of the invention will be apparent during the course of the following description.

In the accompanying drawing forming a part of this specification and in which like numerals are employed to designate like parts throughout 20 the same:

Figure 1 is a front elevational view of a coat with the lapel fastener device embodying this invention properly associated therewith;

Figure 2 is a front elevational view of the lapel fastener device shown positioned in Fig. 1;

Figure 3 is an edge elevational view of the fastener structure disclosed in Fig. 2;

Figure 4 is a transverse sectional view taken on line 4—4 of Fig. 2;

30 Figure 5 is a plan view of the rear fastener member; and

Figure 6 is a plan view of the front fastener member.

In the drawing, wherein for the purpose of illustration is shown a preferred embodiment of this invention, the reference character A designates in its entirety a coat or jacket which has applied to its lapels a the lapel fastener designated in its entirety by the reference character B.

40 Figs. 5 and 6 respectively disclose the rear and front members which are properly associated to form the lapel fastener embodying this invention. It is to be understood that these two members are formed of cardboard, or the like, of suitable thickness and grade of material to afford a reasonable degree of resiliency.

45 The rear member 10, see Fig. 5, when in blank form includes an elongated body portion 11 which is shaped to provide a pair of oppositely projecting tongues 12. These tongues are reduced or sharpened at their extremities 13. Projecting laterally from the central portion of this body 11 is a tab 14.

50 The front member, designated in its entirety by the reference character 11, also is shaped to pro-

vide a body portion 15 which includes the oppositely extending tongues 16, reduced or sharpened at the extremities 17. A laterally extending, centrally positioned tab 18 also is carried by the body 15. It will be noted by comparing Figs. 5 and 6 5 that the body 15 of the front member is shorter than the body 11 of the rear member, so that when these two members are superimposed, as shown in Figs. 2 and 3, the sharpened extremities 13 of the rear member 10 will project beyond the sharpened extremities 17 of the front member 11.

The tab 14 of the rear member 10 is adapted to be folded on the line 19 so that it will overlie the central portion of the body 11. The tab 18 of the front member 11 is adapted to be folded 15 on the line 20 so that it will overlie the central portion of the body 15. With these tabs 14 and 18 folded as just described, the two members 10 and 11 are arranged so that the bent over tabs 14 and 18 will interlock with each other, as best disclosed in Fig. 4. This interlocking is accomplished by inserting each tab into the space between the tab and body portion of the other member. With the two members superimposed in this manner, they will be retained in spaced parallelism by the interlocked tabs and the spacing between the two members will be equal to the combined thicknesses of the two tabs. To retain the members in this proper relation, the fastening member in the form of a staple 21, or the like, is driven through the central portions of both of the members 10 and 11 and the interlocked tabs 14 and 18, as best shown in Figs. 2 and 3.

35 The lapel fastener now is completely formed and may readily be applied to the lapels of a coat by merely threading the lapels into the spaces left between the superimposed tongues 12 and 16 of the members 10 and 11, as clearly illustrated in Fig. 1. As the fastener is to be delivered to the customer who owns the coat, the front of the fastener provides an appropriate place for advertising matter.

40 It is to be understood that the form of this invention herewith shown and described is to be taken as a preferred example of the same and that various changes in the shape, size and arrangement of parts may be resorted to without departing from the spirit of the invention or the scope of the subjoined claims.

45 Having thus described the invention, I claim:

50 1. A lapel fastener of the type described comprising a pair of double tongue shaped members, a centrally positioned, laterally extending tab carried by each member and adapted to be bent

back upon the body portion of its member, said members being arranged with their tabs in engagement with each other so that said tabs will maintain said members in spaced parallel relation, and means for connecting said members in such relation.

2. A lapel fastener of the type described comprising a pair of double tongue shaped members, a centrally positioned, laterally extending tab carried by each member and adapted to be bent back upon the body portion of its member, said members being arranged with their tabs in interlocked, overlapped relation so as to hold said members spaced distances equal to the combined thickness of bore of said tabs, and securing members passed through both of said members and their tabs.

3. A lapel fastener comprising a pair of double elongated members, a laterally extending tab carried by each of said members and adapted to be bent back upon the body portion of the member, means to secure said members in parallelism, and with said tabs serving to maintain said members in spaced relationship when so secured. 5

4. A lapel fastener comprising a pair of double tongue-shaped members, tabs integral therewith, and a securing means, said members being maintained in spaced parallelism by said integral tabs folded between said members and by said securing means. 10
